UNITED STATES PATENT OFFICE.

OSCAR M. THOMSON, OF PHILADELPHIA, PENNSYLVANIA, ASSIGNOR TO AMERICAN MILK PRODUCTS CORPORATION, OF NEW YORK, N. Y., A CORPORATION OF DELAWARE.

ILLUSORY ADVERTISING DEVICE.

Application filed November 9, 1923. Serial No. 673,745.

To all whom it may concern:

Be it known that I, OSCAR M. THOMSON, a citizen of the United States, and resident of Philadelphia, in the county of Philadelphia, 5 and State of Pennsylvania, have invented certain new and useful Improvements in an Illusory Advertising Device, of which the following is a specification.

This invention relates to an illusory advertising device and is particularly applicable to the display and advertising of containers for milk or other food products and the general object of this invention is to provide an attractive display which in its 15 operation will cause the observer to see a display container during one operation of the device, but at the next operation of the device said display container will not be visible. More particularly the object of the 20 invention is to provide means especially adaptable to the operation of a container for food products and the like by which operation enables the container to be visible and invisible by the operation of the device.

25 For this purpose the invention consists of the novel structure shown in the drawings and hereinafter to be described and finally pointed out in the claims.

In the accompanying drawings,

30 Figure 1 is a front view of my improved device showing the display container in position and visible to the observer;

Figure 2 is a vertical section taken on line 2—2 of Figure 1 in which the visible 35 position of the container is shown in full lines and in which the position of the container invisible to the observer is shown in dotted lines;

Figure 3 is a view of a portion of the 40 operating parts seen from line 3—3;

Figure 4 is a plan view, partly in section, of the container and the parts within the container; and

Figure 5 is a section of the container taken 45 on line 5—5 of Figure 4.

Similar characters of reference indicate corresponding parts throughout the various views.

Referring to the drawings and more particularly to Figure 2, the casing 10 is formed like a box in which the seven sides form closed walls but the eighth side is open. Within the casing 10 there is arranged diagonally of the casing a mirror 11 that extends from the corner 12 towards the center

part 13 of the casing. Preferably the interior walls of the casing 10 are provided with a suitable lining as green blotting-paper, or green cloth or the like and the reflection of the color of this lining into the 60 mirror 11 is such that it is almost impossible to see that a mirror exists or where the mirror begins or ends.

To carry out this illusion the wall of the casing 10 is provided with a diagonal slot 65 14 which is symmetrical with the angular position of the mirror 11. To further carry out the illusion, lamps 15 depend from the upper wall of the casing and these reflect the light against the interior walls of the casing and against the mirror, so as to make it very difficult, excepting to one who is initiated, to ascertain that a mirror actually exists. The end edge of the mirror 11 abuts against a nickel-plate rod 16, which extends 70 from side wall to side wall and at the rear of this rod 16 there is arranged a shaft 17 which has means thereon for being rotated and also means for holding the container. The means for rotating the shaft 17 comprise a pinion 18 secured to the end of the shaft at the exterior of the casing and this pinion 18 meshes with a pinion segment 19 arranged on a plate 20 secured to a shaft 75 21 bearing within a plate 22 secured by screws 23 to the outer wall of the casing. To the pinion plate 20 and to the shaft 21 is secured a lever arm 24 which is engaged by a vertically arranged rod 25, the lower end of which is not shown in the drawings, but which is operated by a suitable mechanism which in turn is operated by an electric motor which causes the lever arm 24 to move down and up at stated periods. The movement of the pinion plate 20 rotates the pinion 18 and hence the shaft 17. The plate 22, the lever arm 24, the pinion 18 and the pinion plate 19 are arranged within an auxiliary casing 27 so as to hide the same 80 from view.

The shaft 17 has secured thereto a sleeve 30 and this sleeve has a portion 31 extending therefrom to which is secured an elbow member 32 having an extension 33 which enters the container. The free end of the extension 33 seats in a bearing 34, forming part of the interior of the container and at the other side of the container the extension 33 has a sleeve 36 having a projection 37 100 which is engaged by one end of a spring 105 110

38, the other end of which is secured to the container at 39. Exterior of the container 35 and at the elbow member 32 there is a sleeve 40, and between this sleeve 40 and the sleeve 36 the wall of the container passes. Within the container 35 there is arranged a mass of heavy material as lead or the like, indicated by 41. Exterior of the shaft 17 a helical spring 42 is arranged, one end of 10 which is secured to the sleeve 43 of the shaft 17 and the other end of which is secured at 44 to the wall of the casing 10.

At the open side of the casing 10, there is arranged an openable and closable front 15 door 50, shown in Figure 2 as in full lines, but partly broken away, and shown in its open position, and in dotted lines in its closed position and this door 50 is supported by angular member 51 which is pivoted at 52 20 to a bracket 53 secured to the lower part of the casing 10. The angular member 51 has its end fastened to a spring 54 which in turn is fastened to a rod 55 operated by mechanism not shown and which acts in unison 25 with the mechanism operating the rod 25 which rotates the shaft 17.

The operation of the device is as follows: The mechanism below the casing 10 which is not shown is set into operation and thereby 30 by the rod 25 and also the rod 55 is vertically reciprocated and thereby the shaft 17 is rotated and the door 50 opened and closed. When the door 50 is open the container 35 is in the position shown in Figure 1 and 35 Figure 2 and is visible to the observer. The door 50 is then closed and thereafter it is opened and when the door is opened and brought into the position shown in Figure 2 as in full lines there shown, the container 40 35 is not visible to the observer, since it has taken the position shown in dotted lines in Figure 2. This is due to the fact that the shaft 17 is rotated and as the shaft 17 rotates it moves the elbow member 32 into the 45 position shown in dotted lines in Figure 2 and from this first dotted line position the continued rotation of the shaft 17 moves the container into the lowermost dotted line position at the rear of the mirror. As the 50 shaft 17 rotates the elbow member 32 moves the container 35 away from the visible position shown in Figure 1 and as this movement takes place the container 35 turns around the extension 33 against the action 55 of the spring 38 and continues to move around the extension 33 until the weight 41 completely turns the container around the extension 33 into the position shown in Figure 2 at the rear of the mirror. The container 60 is thereby given a turn movement from its upright position as illustrated in Figure 1 to its horizontal position as illustrated in Figure 2 in dotted lines. The return movement of the shaft 17 raises the 65 elbow member 32 and hence the container 35

and as the container 35 is raised the spring 38 in conjunction with the weight 41 serves to again turn the container until it reaches the uppermost dotted line position, when by an almost instantaneous movement of the 70 container 35 around the extension shaft 33, the container is brought into upright position. To assist in holding it in this position the container 35 is provided with an extension 57 which abuts against the elbow mem- 75 ber 32.

Thus by the operation of suitably timed mechanism the front of the casing is opened or closed and when it is open the container is visible as in the position shown in Figure 1. Then the door is closed and during the closing of the door the container is moved from its visible to its invisible position and when the door is again opened nothing can be seen of the container. 80 85

The container may be provided with a suitable label representing a well-known brand of evaporated milk or other food product and the device may thereby be used for advertising such a brand of food product, since the average observer will be attracted by the illusionary character of the display device and thereby the device is admirable and very advantageous to calling 90 attention to the article to be advertised. 95

I have shown an embodiment of my invention but changes may be made therein without departing from the spirit of my invention as defined in the appended claims. 100

What I claim is:

1. An illusory advertising device comprising a casing, a mirror diagonally arranged within the casing, a shaft at the rear of and below the upper edge of the mirror, a container moved by the shaft and means 105 between the shaft and the container for moving it from an upright vertical position at the top of the mirror through a turning movement to a horizontally arranged position below and at the rear of the mirror. 110

2. An illusory advertising device comprising a casing, a mirror arranged diagonally within the casing, a horizontal shaft at the rear of and below the upper edge of the mirror, a lever arm mounted on said shaft for movement therewith, a container supported by said lever arm, a weight within the container and spring operated means between the container and the shaft within the container for holding it in a vertical position when the container is supported above the mirror causing it to turn to a horizontal position when the arm is rotated downwardly behind the mirror. 115 120

3. An illusory advertising device comprising a casing, a mirror arranged diagonally within the casing, an openable and closable door at the front of the casing, a shaft within the casing at the rear of and below the upper edge of the mirror, a lever 125 130

arm mounted on said shaft for movement therewith and in unison with the means for opening or closing the door, a container pivotally supported by said lever arm, a 5 spring having one end secured to the arm and the other to the container, a weight within the container, a projection at the exterior of the container adapted to engage with the lever arm when the arm is in its 10 upper position for holding the container in a vertical position, and means for moving the door and the shaft supporting the lever arm whereby the container is pivotally moved in respect to its shaft from upright 15 vertical position to horizontal position at the rear of the mirror.

4. An illusory advertising device comprising a casing, a mirror arranged diagonally within the casing, a horizontal shaft at

the rear of the mirror and below the upper 20 edge thereof, a lever arm mounted on said shaft for movement therewith, said lever arm adapted to extend above the upper edge of the mirror in one of its positions a container supported by the free end of said lever 25 arm, and means for holding said container in a vertical position when the container is supported above the mirror and in the front thereof, and the lever arm is brought above the upper edge of the mirror and for 30 causing it to turn to a horizontal position when the arm is rotated downwardly behind the mirror.

In testimony that I claim the foregoing as my invention, and have signed my name 35 hereto.

OSCAR M. THOMSON.
